CARBURETOR

Leonard D. Boyce, Maplewood, Mo., assignor to
 Carter Carburetor Corporation, St. Louis, Mo.,
 a corporation of Delaware

Application March 28, 1946, Serial No. 657,859

7 Claims. (Cl. 48—107)

1

This invention relates to carburetors for internal combustion engines and consists particularly in novel means for aiding in the vaporization of the fuel supply.

In the present type of automotive engines, fuel is drawn by suction from the main and idling nozzles of the carburetor and conducted through the branches of the intake manifold to the cylinders. At best, the fuel is imperfectly vaporized and this tends to cause hard starting, poor distribution, loss of fuel, and improper performance. These difficulties are partly eliminated by a "hot spot" built on the manifold riser to heat the mixture. Although the admission of exhaust gases to the "hot spot" is usually controlled by a valve in an effort to adjust the heat in accordance with the condition of the fuel, such an arrangement, nevertheless, results in loss of volumetric efficiency and does not completely solve any of the difficulties mentioned.

There have been carburetor devices which have provided for igniting a portion of the fuel and feeding the resulting extremely hot gases into the mixture conduit to aid in vaporizing the main fuel supply. These have not been wholly satisfactory since there was no way to adjust the mixture proportions as the carburetor suction varied so that the flame frequently went out. Moreover, these devices either were not connected to the idling system, or else they adversely affected idling operation.

One object of the present invention is to provide a fuel vaporizer utilizing a suction operated burner with means to supply constant proportions of fuel and air to the burner.

It is another object to provide a fuel vaporizer, of the type utilizing ignited gases, with means for applying the vaporizing effect thereof to the idling fuel system.

It is a further object to provide common means for supplying hot gases to both the main and idling fuel systems without upsetting the normal functioning of either.

It is another object to provide means for supplying hot gases directly to the Venturi tube into which the main fuel nozzle discharges.

It is still another object to provide means to thoroughly vaporize or gasify the fuel without adversely affecting the volumetric efficiency of the engine.

2

These objects and other more detailed objects hereafter appearing are attained by the device illustrated in the accompanying drawing in which

Fig. 1 is a vertical section and side view illustrating a carburetor of the automotive type having the invention applied thereto.

Fig. 2 is a wiring diagram showing parts of the ignition system.

The carburetor shown includes a downdraft mixture conduit 1 having an elongated, central Venturi tube 2. The admission of air to the upper end of the conduit is controlled by a choke valve 3 which is controlled for cold starting and warm-up by a thermostat 4, a latching segment 5, and a suction actuated detent 6, as further described and claimed in my co-pending application Serial No. 599,658, filed June 15, 1945. The discharge of mixture is manually controlled by a throttle valve 7 mounted near the lower end of the carburetor. The carburetor is mounted on the intake manifold riser 8, the usual "hot spot" at this point being omitted.

Formed as a part of the carburetor body adjacent the mixture conduit is the usual constant level chamber 9 having a metering orifice element 10 in the lower part thereof controlled by a metering pin 11 which may be operated in any suitable way (not shown) as by a connection to the throttle, or by a suction responsive device. A main fuel nozzle 12 connects metering orifice 10 to the throat of Venturi tube 2 near the anterior end thereof. A chamber 13 of substantial length and cross section extends along the mixture conduit and opens at its lower extremity into the conduit through idling ports 14 adjacent and posterior to the edge of throttle 7 when closed. Chamber 13 is connected by passages 15, 17, and 18 to the base of main fuel nozzle 12 and thence, through metering orifice 10 to the constant level chamber. These passages and chamber 13 supply idling fuel to the engine when the throttle is closed. Passage 15 connects with chamber 13 about midway of its length.

An auxiliary air tube or passage 20 extends from the upper portion of the mixture conduit around the choke valve and thence into the top or anterior end of Venturi tube 2. This auxiliary passage has a Venturi tube 21 into which discharges an auxiliary fuel supply nozzle 22 controlled by a metering needle 23 carried by an ad-

justing screw 23a and having an air bleed 23b. Nozzle 22 is connected by a cross passage 24 to the constant level chamber for supplying fuel by engine suction to the auxiliary air passage. The admission of air to this passage is controlled by an unbalanced, weighted, normally closed valve 25 and the discharge of gases into Venturi tube 2 is controlled by a similar valve 28.

A spark plug 27 is mounted on auxiliary air passage 20 just posterior to Venturi tube 21 and is connected by wire 28 to the ground side of spark coil secondary 29. This plug is grounded through the carburetor body and provides for constantly igniting the mixture within the auxiliary air passage whenever the engine is in operation. The usual distributor and breaker devices are shown at 30 and 31 connected in the ignition system with battery 32. The flame and burned gases are led through the auxiliary passage into chamber 13 during idling and part throttle operation, and into Venturi tube 2 when the throttle is opened so as to produce sufficient suction within Venturi tube 2 to open weighted valve 26. When valve 26 is closed, no air can be drawn back through the normal discharge end of passage 20 into the idling system. Weighted air valve 25 in passage 20 adjusts the supply of air to the burner in accordance with the suction so as to insure an approximately uniform combustible mixture.

The resultant hot gases entering Venturi tube 2 aid in thoroughly vaporizing the main fuel supply, but the flame is effectively quenched by the liquid fuel emerging from the main fuel nozzle (the auxiliary mixture being cooled and rendered too rich to burn thereby). Long chamber 13 forming part of the idling passage similarly serves to quench the flame and to provide for complete gasification of the idling fuel. The long Venturi tube 2 provides for complete gasification of the main fuel supply so that a dry gas emerges from the tube for mixing with the cold air in the mixture conduit. Since the heating is applied directly to the relatively small volume of fuel and not the main body of air around tube 2, the temperature of the whole body of mixture supplied by the carburetor is not raised sufficiently to materially affect the volumetric efficiency of the engine.

The carburetor shown may be used with heavier fuels than are normally supplied for automotive use because of its superior vaporizing properties. The more even and rapid distribution of fuel to the cylinders results in easier starting and improved performance and economy. Adequate means are provided for maintaining, controlling, and quenching the flame so that maximum advantages are obtained. The gasified fuel will be carried in stable, well mixed condition through the manifold to the cylinders so that additional heating of the mixture is not necessary. Since no vaporization occurs at the idle ports or around the throttle, icing at these points is greatly reduced or eliminated.

The invention may be modified in various respects as will occur to those skilled in the art and the exclusive use of all modifications as come within the scope of the appended claims is contemplated.

I claim:

1. In a carburetor, a mixture conduit, a main fuel nozzle discharging thereinto, an auxiliary air chamber, a fuel supply for said chamber, means to ignite the fuel and air in said chamber, a passage for leading the resulting hot gases into said conduit to aid in vaporizing the fuel there-

in, an idling fuel duct communicating with said passage, and a flow responsive check valve in said passage between said duct and that portion of said passage which enters said conduit.

2. In a carburetor, a mixture conduit having a throttle valve therein, an idling fuel passage discharging into said conduit posterior to the edge of said throttle valve when closed, an auxiliary air passage communicating with said idling passage, a fuel supply for said auxiliary passage, and means to ignite the fuel and air in said auxiliary passage for supplying hot gases to said idling passage and thereby aid in the vaporization of fuel therein.

3. In a carburetor, a mixture conduit having a throttle valve therein, a fuel supply chamber, an idling fuel passage extending from said chamber and discharging into said conduit posterior to the edge of said throttle when closed, said passage including a vaporizing chamber of substantial length, an auxiliary air passage communicating with said vaporizing chamber, an auxiliary fuel supply for said air passage, and means to ignite the fuel and air in said auxiliary passage for supplying hot gases of said vaporizing chamber, said vaporizing chamber being of substantial length whereby the flame is quenched before entering said mixture conduit.

4. In a carburetor, a mixture conduit having a throttle valve therein, an idling fuel passage discharging into said conduit posterior to said throttle when closed, an auxiliary air passage, an auxiliary fuel supply for said air passage, means to ignite the fuel and air in said auxiliary passage for supplying hot gases to said idling passage to aid in the vaporization of fuel therein, and a valve in said auxiliary passage anterior to said auxiliary fuel supply to control the admission of air to said auxiliary passage.

5. In a carburetor, a mixture conduit having a throttle valve therein, a main fuel nozzle discharging into said conduit anterior to said throttle, an idling fuel passage discharging into said conduit posterior to said throttle, an auxiliary air passage opening into said conduit anterior to said main fuel nozzle and having a connection to said idling passage, an auxiliary fuel supply for said auxiliary air passage, means to ignite the fuel and air in said auxiliary passage to supply hot gases to said mixture conduit anterior to said main fuel nozzle and to said idling passage, and a pressure responsive valve in said auxiliary passage posterior to its connection to said idling passage to prevent the drawing of air into said idling passage from the discharge end of said auxiliary air passage.

6. In a carburetor, a mixture conduit having a choke valve controlling the admission of air thereto, a Venturi tube in said conduit posterior to said choke valve, a main fuel nozzle discharging into said Venturi tube, an auxiliary air passage leading from said conduit anterior to said choke valve around said choke valve and thence into said Venturi tube, an auxiliary fuel passage discharging into said air passage, means to ignite the fuel and air in said auxiliary passage, and means in the outlet of said auxiliary passage to control the discharge of hot gases therefrom.

7. In a carburetor, a mixture conduit having a throttle valve therein, an elongated Venturi tube in said conduit, an idling fuel passage including an elongated and enlarged chamber portion, a main fuel nozzle discharging into the anterior portion of said Venturi tube, an auxiliary air passage also discharging into the anterior end of

said Venturi tube and having a connection to said idling chamber, an auxiliary fuel supply for said air passage, means to ignite the fuel and air in said air passage for supplying hot gases to said Venturi tube and said idling chamber to aid, respectively, in vaporizing the main and idling fuel supplies, and a valve in said auxiliary passage between said idling passage and said conduit preventing back flow of air from said conduit into said idling chamber.
